CLAIM

The ornamental design for a golf shoe cleaner, as shown and described.

DESCRIPTION

FIG. 1 is a top right perspective view of a golf shoe cleaner showing my new design;

FIG. 2 is a side elevational view of the head portion of the new design depicted in FIG. 1, the rear perspective view of the shaft portion being a mirror image of the front perspective view depicted in FIG. 1;

FIG. 3 is a top plan view of the head portion of the new design depicted in FIG. 1;

FIG. 4 is a left side elevational view of the head portion of the new design depicted in FIG. 1;

FIG. 5 is a right side view of the head portion of the new design depicted in FIG. 1; and,

FIG. 6 is a bottom plan view of the head portion of the new design depicted in FIG. 1.

The handle portion is only partially shown in FIGS. 2 through 6 for convenience of illustration.
